(57) **CLAIM**

The ornamental design for a hat with LED lights, as shown and described.

DESCRIPTION

FIG. 1 is a front perspective view of a hat with LED lights arranged like truck cab clearance lights, showing an embodiment of my new design;

FIG. 2 is a front perspective view of the hat shown in FIG. 1 with the lights illuminated;

FIG. 3 is a top view of the hat shown in FIG. 1;

FIG. 4 is a bottom view of the hat shown in FIG. 1;

FIG. 5 is a right side view of the hat shown in FIG. 1;

FIG. 6 is a left side view of the hat shown in FIG. 1;

FIG. 7 is a front view of the hat shown in FIG. 1;

FIG. 8 is a rear view of the hat shown in FIG. 1;

FIG. 9 is a front perspective view of an alternative embodiment of my design, having a curved hat brim;

FIG. 10 is a front perspective view of the hat shown in FIG. 9 with the lights illuminated;

FIG. 11 is a top view of the hat shown in FIG. 9;

FIG. 12 is a bottom view of the hat shown in FIG. 9;

FIG. 13 is a right side view of the hat shown in FIG. 9;

FIG. 14 is a left side view of the hat shown in FIG. 9;

FIG. 15 is a front view of the hat shown in FIG. 9; and,

FIG. 16 is a rear view of the hat shown in FIG. 9.

The broken lines shown in the drawings depict portions of the hat with LED lights that form no part of the claimed design. The lines emanating from the lights in FIGS. 2 and 10 depict illumination and form no part of the claimed design.
